UNITED STATES PATENT OFFICE.

JAMES A. McALLISTER, OF FREDERICTON, NEW BRUNSWICK, CANADA.

DUPLEX BRICK.

SPECIFICATION forming part of Letters Patent No. 339,799, dated April 13, 1886.

Application filed August 11, 1885. Serial No. 174,116. (No model.)

To all whom it may concern:

Be it known that I, JAMES A. McALLISTER, of Fredericton, in the Province of New Brunswick and Dominion of Canada, have invented 5 a new and Improved Duplex Brick, of which the following is a full, clear, and exact description.

My invention relates to the construction of brick or building-blocks; and its object is to 10 construct a brick that can be easily made and handled, and which, when used, will produce a firmly-united wall that will be practically frost and moisture proof.

The invention consists of two ordinary-sized 15 brick that are united by a connecting neck or web, the surfaces of the brick being indented, for purposes which will be hereinafter specifically explained.

Reference is to be had to the accompanying 20 drawing, forming a part of this specification, which is a plan view of a brick made in accordance with my invention.

My improved double or duplex brick consists of two blocks, A A', substantially in the 25 form and proportion of an ordinary brick, and which are united by a neck or web, B.

The upper and lower faces and the ends of the brick are formed with indentures C C, so 30 that when the brick are built up in courses the mortar will enter said indentations and thereby obtain a firmer grip upon the brick. The parts A A' being spaced, as shown, by the neck B, there will be a dead-air space in any

wall built from such brick as have been described, which, as is well known, will render 35 the wall practically frost and moisture proof.

Another advantage of my improved form of brick is, that it can be more easily made than two single brick, as it requires but a single handling and pressing to make it, and then, 40 too, the brick-layer can build more wall in a day when using my brick than he could with the ordinary form.

I am aware of the brick forming the subject-matter of Letters Patent No. 189,676, of April 45 17, 1877, wherein there is illustrated and described a brick formed in two parts and united by a web, and designed to interlock when set up in a wall; and I make no claim to the subject-matter disclosed in said patent, my invention being confined to a brick which may be used to form a wall with a central air-space.

Having thus described my invention, I claim as new and desire to secure by Letters Patent— 55

1. An improved building-brick, consisting of the rectangular blocks A A', united by a neck, B, substantially as described.

2. An improved building-brick, consisting of the blocks A A', united by a neck, B, and 60 formed with the indentations C C, substantially as described.

JAMES A. McALLISTER.
